(57) **CLAIM**

The ornamental design for a sandal, as shown and described.

DESCRIPTION

FIG. 1 is an upper perspective view of a sandal showing my design;

FIG. 2 is a lower perspective view of the sandal of FIG. 1;

FIG. 3 is a bottom plan view of the sandal of FIG. 1;

FIG. 4 is a top plan view of the sandal of FIG. 1;

FIG. 5 is right side elevational view of the sandal of FIG. 1;

FIG. 6 is left side elevational view of the sandal of FIG. 1;

FIG. 7 is a front elevational view of the sandal of FIG. 1; and,

FIG. 8 is a rear elevational view of the sandal of FIG. 1.

Straps of the sandal are shown in broken line for illustrative purposes only and form no part of the claimed design.

1 Claim, 4 Drawing Sheets
